UNITED STATES PATENT OFFICE.

FRANCIS T. LEILICH, OF BRIDGEPORT, CONNECTICUT, ASSIGNOR TO THE WHEELER & WILSON MANUFACTURING COMPANY, OF SAME PLACE.

BUTTON-HOLE SEWING-MACHINE.

SPECIFICATION forming part of Letters Patent No. 434,155, dated August 12, 1890.

Application filed June 8, 1889. Serial No. 313,580. (No model.)

To all whom it may concern:

Be it known that I, FRANCIS T. LEILICH, a citizen of the United States, residing at Bridgeport, in the county of Fairfield and State 5 of Connecticut, have invented certain new and useful Improvements in Button-Hole Sewing-Machines; and I do hereby declare the following to be a full, clear, and exact description of the invention, such as will enable others skilled in the art to which it appertains 10 to make and use the same.

My invention relates to certain new and useful improvements in button-hole sewing-machines; and the object of my invention is 15 to provide a simple and efficient device for rapidly stitching the sides of a button-hole with a series of stitches composed of two needle-threads, a third thread interlocked with them above the goods, and a fourth thread 20 interlocked with said needle-threads below the goods. This peculiar stitch, although shown, does not constitute a part of this invention. During the process of stitching the button-hole the same is cut automatically, 25 and when the stitching is completed the hole is ready for the button without further manipulation.

With these ends in view my invention consists in the construction and combination of 30 co-operating mechanical elements hereinafter fully and in detail set forth, and then recited in the claims.

In order that those skilled in the art to which my invention appertains may fully 35 understand its construction and operation, I will describe the same in detail, reference being had to the accompanying drawings, which form a part of this specification, and in which—

40 Figure 1 is an elevation, partly in section, of the front side of my machine, the loop-taking mechanism being removed; Fig. 2, a similar view from the rear side, showing the loop-taking mechanism; Fig. 3, a 45 plan view, parts of the arm being broken away to show the mechanism within; Fig. 4, a plan view of the bed-plate, a portion of which is shown as broken away; Fig. 5, an end elevation, the face-plate being removed 50 and a part of the head sectioned. This view is full size. Fig. 6 is a transverse vertical sec-

tion taken at the line *y y* of Fig. 1 and looking toward the right hand of Fig. 1; Fig. 7, a detail section taken at line *ZZ* of Fig. 4; Fig. 8, a detail section at line *xx* of Fig. 7; Fig. 55 9, a detail of the lever which appears at the left of the interior of the arm at Fig. 6; Fig. 10, a transverse section taken at line *uu* of Fig. 2, looking toward the right hand of Fig. 2; Fig. 11, a detail section at line *ww* of Fig. 60 1, looking toward the left of such figure; Fig. 12, a detail section taken at line *tt* of Fig. 1, looking toward the right; Fig. 13, a detail plan view of the presser-arm and presser-foot; Fig. 14, a detail front elevation of the 65 face-plate, showing the lead of the threads; Fig. 15, a detail sectional view showing the mechanism whereby the purler is operated; Fig. 16, a detail side elevation, partly in section, taken at right angles to Fig. 15; Fig. 17, 70 a detail section at line *ss* of Fig. 15; Fig. 18, a diagrammatic view of a partially-completed button-hole held in the clamp; Fig. 19, a similar view, but showing the hole stitched as to one side, partially stitched as to the other 75 side, and partially cut; Fig. 20, a detail section at line *rr* of Fig. 2.

Like reference-numbers denote the same parts in all the figures of the drawings.

1 is the bed-plate. 2 is the vertical rear 80 portion of the arm, and 3 the tubular portion thereof, which carries at its end the needle-bar 4, on which two needles 5 are mounted. The needle-bar is driven from the main shaft 6 by a crank-disk and link 7, and upon the 85 rear end of said shaft is a band-wheel 8.

9 is the shuttle-shaft extended longitudinally beneath the bed. It is preferably operated from the main shaft by a pitman 10, having at its center a sliding connection with 90 fulcrum 11, a crank-connection with the main shaft, and also a crank-connection with the shuttle-shaft.

12 is a loop-taking device driven from the outer end of the shuttle-shaft. While any 95 lock-stitch-sewing device might be employed, I prefer and have shown the rotary shuttle system, the shuttle of which may, as convenience dictates, be arranged to revolve either in a horizontal or in a vertical plane. Journaled within and transversely to the hollow rear portion of the arm is a shaft 13. (See

Figs. 3 and 6.) Near one end it carries a ratchet-wheel 14. (Shown at the figures above referred to and also at Fig. 1.) This ratchet-wheel and its shaft and a disk at its other end, which will be hereinafter more particularly referred to, are actuated from the main shaft through a cam 15, which through an arm and stud 17 (see Figs. 3 and 6) imparts axial to-and-fro movement to a short rock-shaft 18, 5 journaled above the ratchet. This rock-shaft has upon its outer end a downwardly-extending and segmentally-slotted arm 19. (See Fig. 1.) By means of a link 20, adjustable in the segment, a to-and-fro movement about its 15 fulcrum-point is imparted to a lever 21, whose upper end is provided with an inwardly-projecting pivoted pawl 22, which engages the peripheral teeth on the ratchet. The adjustment of which the link is capable on the slotted segment admits of a greater or less sweep to the lever, and consequently of a varied engagement by the pawl, so as to move the ratchet-wheel one, two, or more steps at each 20 stitch, as may be found convenient for the accomplishment of the work in hand. The lever 21 is preferably fulcrumed about a screw 23, which is tapped into the center of the shaft 13.

In the inner face of the ratchet-wheel 13 is 30 cut a cam-groove 24, which through a shoe or roller running therein operates a lever 25 about its fulcrum 26. (See dotted lines, Fig. 1, and also Figs. 6 and 9.) The lower end of this lever, as at 27, is provided with a segmental adjusting-slot, with which a link 28 is 35 engaged by a binding-screw, the other end of said link being pivotally attached to a lever 29, whose upper end is fulcrumed to a bracket in the arm and whose lower end projects below the plane of the bed-plate. (See Figs. 1, 4, and 6.) The lower end of this lever is universally jointed to a link 30, whose outer end is adjustably secured to a slide-bar 31, upon the forward end of which is mounted the 40 cloth-plate 32. The slide-bar has its bearing in ways formed in a carriage 33, which may be moved transversely to the bed in ways 34, in which it is mounted. The means for effecting this transverse movement will be presently 45 described. At its rear end the slide-bar 31 carries an upward projection 35, to allow movement for which the bed-plate is slotted, and upon this projection as a base is pivoted an overhanging presser-foot arm 36, carrying 50 at its end an open presser-foot 37, which binds the goods to be sewed to the open cloth-plate, the foot and plate forming a cloth-clamp. A slot 38 at the base of the presser-foot arm, in which is arranged a cam 39, serves, in connection with said cam, to effect the clamping of 55 the foot downward or its release.

The purpose of the parts just described and indicated by the numerals from 24 to 39, inclusive, is to feed the cloth-plate, presser-foot, and goods forward and back beneath the needle-bar.

40 is a cam-groove cut in the outer surface

of the ratchet-disk 13. For the greater part of its circumference this groove is circular as to the center of the disk; but at two points, 70 opposite or nearly so, it has a sharp cam-surface. This is for the reason that said cam is intended to effect in the elements operated thereby two positive and well-defined movements at each revolution of the ratchet-wheel. 75

41 is a lever pivoted outside the arm at 42 and connected to the cam-groove just described by a stud or roll, which projects inward through a slot in the arm-plate. (See Fig. 1.) The lower end of this lever (see Figs. 80 4, 6, 7, and 8) is attached by a universal joint to a segmentally-slotted block 43, which is pivotally attached to a bracket 44 on the under side of the bed-plate.

45 is a pitman secured to the slotted block 85 by a binding-screw 46, so as to be adjustable in the segmental slot at the will of the operator. (See Fig. 4.) The outer end of the pitman 45 is pivotally secured to one arm of a bell-crank lever 47, whose elbow is pivoted 90 beneath the bed-plate. The other arm of the bell-crank is connected through a link 48 to the carriage 33. (See Fig. 4.)

The parts just described and identified by numerals from 40 to 48 serve to shift the carriage 33, and with it the slide bar, cloth-plate, &c., transversely at the time when the end of the longitudinal feeding movement of the carriage has been reached, so that the return movement of the cloth beneath the needles 95 may be in line parallel with the line of stitches already made.

The upper end of the lever 41 is connected by a bar 49 with a bell-crank 50, which latter is pivoted near the end of the arm of the machine. The lower arm of the bell-crank is attached to the upper end of a rack 51, arranged to have a vertical movement in ways 52 by means of said bell-crank. The rack 105 engages a pinion upon the transverse purler-shaft, (see Fig. 5,) and is adapted to impart to the shaft and purler their proper shifting motion at the same time that the shift of the carriage at the under side of the bed is accomplished by means of the lower end of the 110 lever 41.

The mechanism whereby the purler-finger is operated will now be described. At the lower end of the head is arranged a sleeve 54, surrounding the needle-bar and movable 120 upon the latter as an axis. The central portion of this sleeve (see Figs. 5 and 15) is spirally threaded, the threads being of coarse pitch, and to the number of, say, five or six. The lower end of the sleeve has secured thereto 125 the bent purler-finger 55, having an eye at its point, through which the purler-thread is led.

56 is a shaft journaled transversely to the head just behind the needle-bar, and upon a sleeve 57, splined to said shaft, is mounted a 130 spirally-threaded pinion 58, similar to and meshing with the spirally-threaded portion of the sleeve. One end of said shaft projects beyond its journal and carries the pinion 59,

heretofore described as engaged and adapted to be turned by the rack 51. At the end of the sleeve described as carrying the pinion and as splined to the shaft is a grooved collar 60, which is engaged by pins projecting inwardly from a fork 61 on the end of a downwardly-projecting arm 62. (See Figs. 2, 5, and 17.) The arm 62 is connected to and is moved by a rock-shaft 63, journaled alongside the 10 arm in bearings 64 65. (See Figs. 2, 3, and 20.) At its rear end beyond the bearing 65 said shaft bears a fork 66, engaged by a wiper-cam 67, which latter (see particularly Figs. 2 and 3) is carried by a gear 68. This gear is 15 driven by smaller gear 69 on the main shaft inside the arm, so as to receive one revolution to two of the shaft. This combination of elements, as will be readily understood, imparts an axial vibration to the rock-shaft and likewise to the downwardly-extending arm 62. The forked end of this arm by engaging the grooved collar on the pinion-carrying sleeve 57 will reciprocate the latter lengthwise of the spline, which is between it and the shaft. 20 At each traverse of the sleeve the spiral pinion on the latter will impart to the spirally-threaded sleeve around the needle-bar and to the finger on said sleeve a half-revolution, so that as the machine runs the purler-finger 25 will be swung in a half-circle and return at every other stitch. When the forward movement of the carriage has ceased and the stitching of the first side of the button-hole is completed, the traversing movement of the goods 30 takes place to bring said goods into proper position for effecting the stitching of the second side of the hole parallel with the first side, and as soon as this traverse has taken place the reverse or backward movement of the goods commences. The purler-finger prior 35 to the traverse has been making its semicircular swing at that side of the needle-bar nearer the arm, so as to lay the purler-thread properly beneath the needles. At the reverse movement of the goods it becomes necessary 40 that the purler-finger should make its semicircular movement at the outside of the needle-bar—that is, the side farther from the arm—and this change of position is effected 45 through the bell-crank lever, the rack which it operates vertically, and the pinion 59, engaged by said rack and secured on the end 50 of the transverse shaft to which the sleeve is splined. This movement of the shaft about 55 its axis through the engagement of the spiral pinion with the threaded portion of the sleeve around the needle-bar will impart to the latter a movement about its axis on the needle-bar, and the parts are so adjusted that the 60 proper movement of the bell-crank lever is just sufficient to carry the purler-finger a half-revolution. In this changed position the semi-rotation of the purler is effected in exactly 65 the same manner as at the forward movement of the cloth, except that the arc through which it vibrates has been altered, so that it will sweep from side to side outside the needle-

bar, instead of inside, as in the first or forward movement of the goods.

That portion of the machine by which the cutting or opening of the button-hole is accomplished is as follows: Within the vertical portion of the arm upon the end of the transverse shaft 13 is a disk 70. (See Figs. 2, 3, and 6.) The edge of this disk is engaged 75 by a spring-actuated friction-brake 81, whose function is to prevent any overrunning of the disk or the ratchet-wheel which is on the shaft with it when the machine is running at high speed. Said disk has cut in its inner face a 80 cam-groove, (see dotted lines, Fig. 2,) which groove is cut so as to impart a short forward and a similar backward movement at each revolution to a lever 71, fulcrumed at its lower end to the arm, and whose upper end 85 projects outward through a slot at the top of the arm. To the end of this lever is pivotally attached a connecting-bar 72, whose outer extremity is pivoted to a link 73. The link 73 has its upper end pivotally secured to a lever 90 74, which latter is fulcrumed near its center to a bracket 75 and its lower end engaging by a stud or roll a segment 76, in which it is movable by means of the connecting-bar. The segment forms one arm of a bell-crank lever, 95 whose pivotal point is at the end of the segment, (see Fig. 2,) and the lower arm of the bell-crank engages a cam 77 on the main shaft, whereby an oscillatory movement is imparted to the bell-crank about its center. 100

78 is the cutter-bar, pivotally secured at its upper end to the outer extremity of the lever 74. Just below its center the bar is fulcrumed on a link 79, and at its lower end it carries a curved and downwardly-extending cutter 80, 105 having an oblique sharp edge at its extremity. By means of the cam which operates the connecting-bar the link 73 may be pushed outward, so that its roller is at the end of the segment away from the center on which the bell-crank vibrates, or it may be drawn inward, so that its roller will be immediately over said center. When in the former position, the segment on the bell-crank, through the link and lever, imparts to the cutter-bar and cutter a 110 vertically-reciprocating movement, its sharp oblique edge piercing the fabric between the two lines of stitching at each downward stroke. When the cam-groove in the disk draws the link 73 backward, so that its end 115 rests in the segment over the center of the bell-crank, said link and the lever assume the position shown by the dotted line *a*, Fig. 2. Thereby the cutter-bar is raised and by its fulcrum-link drawn inward, so that its center line 120 is as appears at dotted line *b*, Fig. 2, and the cutter is drawn upward and inward, as shown at Fig. 2. While the end of the link is over the center of the bell-crank it derives no motion therefrom and none is transmitted to the 125 cutter-bar. On the forward motion of the goods, while the cutter is out of action, it will be remembered that the swing of the purler-finger is inside the needle-bar. At this time 130

the cutter is raised and inactive, and the movement of said finger is in no way interfered with. On the backward movement of the goods the cutter operates just behind (in point of time) the needles and purler, so that the hole is cut step by step simultaneously with the stitching of the second side of the button-hole. Meanwhile the purler-finger is moving in the arc of a circle to and fro outside the needle-bar.

In the diagrammatic Figs. 18 and 19, *c* represents the needle-threads, *d* the shuttle-thread, *e* the purler-thread, and the curved dotted line *f* the arc through which the purler-finger travels to lay its thread.

The operation of my invention is as follows: At each turn of the main shaft, whereby a downward stroke of the needles is effected, the loops from both needles are taken by the shuttle and the single shuttle-thread interlocked with them. Just prior to the descent of the needles the purler-finger swings to one side and lays the purler-thread, which is led to the finger from any convenient spool and through any ordinary tension just behind the needles, (see Fig. 18,) one of which at their descent locks the purler-thread. Before the next downward movement of the needles the purler-finger has moved through its arc, (see curved dotted line *f*, Figs. 18 and 19,) and so lays the purler-thread again behind the needles, the opposite one of which locks it in its descent. Meanwhile the goods held in the clamp are advanced one step at each descent of the needle-bar. This effects the feed or longitudinal spacing between the stitches and the zigzag line in which the purler-thread is laid between each alternate stitch on one side and each alternate stitch on the other side. This interlocking with the alternate stitches arises from the fact that the gear 68 only derives one turn from the gear 69 to two turns of the main shaft and said gear. Consequently the arm 62, which is operated twice at each turn of the gear 68 and moves the purler-finger through the engagement of the two spiral pinions, operates said purler-finger once across at each movement of the needle-bar. In starting the button-hole the ends of all the threads should be laid under the presser-foot and securely held by the clamping action thereof, the needle-threads and purler-thread on top of the goods, and the shuttle-thread beneath the goods, as shown at dotted lines, Figs. 18 and 19. The movement of the goods and clamp beneath the needles is effected by means of the lever 29, connected to the slide-bar by 30, and the length of the stitch may be varied by causing the pawl 22 to engage and turn the ratchet-wheel 14 one tooth at a time or more, which may be accomplished by varying the position of the link 20 in the slotted segment 19. The length of the button-hole is governed by the position of the link 28 in the segment 27, whereby the pivoted lever 29 is made to move through a greater or less distance in any given number

of stitches. Through combined adjustments of the links in the segments 19 27 any length of button-hole within the limit of the machine may be made and variations in the number of stitches in any given length of hole be readily accomplished. When the feeding and stitching of the first side of the button-hole have progressed to the length prescribed by segment 27 and its connections, the sidewise movement of the carriage, which brings an unsewed surface of the goods beneath the needle-bar, is accomplished through the lower portion of the lever 41, operated by the groove in the face of the ratchet-wheel, the swinging block beneath the bed-plate, and the links and bell-crank 47. This movement traverses the carriage 33, and as the slide-bar carrying the cloth-plate has a bearing in this carriage it will be readily seen that the goods are traversed under the needles. The length of the traverse, which determines the distance between the two lines of stitching, may be varied by means of the segment in which the screw 46 binds. The time required to make the traverse and which is determined by the incline of the cam in the outer face of the ratchet-wheel, I prefer to arrange to cover four downward strokes of the needle-bar. This may be varied; but I find that four strokes of said bar effects the barring of the end of the button-hole sufficiently well for all practical purposes. As shown at the right hand of diagrammatic Fig. 19, the first stroke after the traverse begins lands the inside needle just across the median line between the rows of stitching. The next, the last forward movement intervening, lands the two needles exactly astride the median line. The third, the first backward feeding movement intervening, lands the needles slightly astride the inside needle-hole of the first barring-stitch and in line therewith, and at the next and last traversing movement the needles pierce the cloth at the proper distance from the first line on stitching with which the second line now commenced is parallel. Simultaneously with the shift of the goods the change of the arc through which the purler-finger moves is effected by the upper end of the lever 41, the connection 49, bell-crank 50, and the rack and pinion operated by said bell-crank, and this change of the purler-finger relative to the needle-bar is accomplished in four steps corresponding to the four steps of the cloth-clamp in the operation of barring. When the backward movement for effecting the second line of stitching commences, the cutter-bar and cutter, which theretofore have been retained out of action and in the position shown at Fig. 2, dotted lines, are thrown downward by means of the cam-actuated lever 71 and connection 72, the link 73 being at the same time pushed outward away from the pivotal point of the constantly-vibrating bell-crank 76, so that a substantially vertical reciprocating movement is imparted to the cutter-bar and cut-

ter at each turn of the main shaft. This movement of the cutter causes the latter to pierce the goods simultaneously with the stitching of the second side of the button-hole and one or two steps behind the needle-bar. At this time, as heretofore explained, the purler-finger is operating at the outside of the needle-bar, so that the free movement of the cutter-bar is in no wise interfered with.

10 The relative positions of the purler-finger and cutter at this time are shown in the diagrammatic Fig. 19.

The bight of the stitch is determined by the distance between the needles, and said bight 15 may be varied at will by adjusting the needles on the bar, so that they may be nearer together or farther apart. They are preferably held in any ordinary adjustable clamp, which I have not thought it necessary to 20 show in detail.

I claim—

1. In a button-hole sewing-machine, the combination, with the needle-bar, the needles carried thereon, and the loop-taker, of the 25 purler-finger journaled about the needle-bar as an axis, means operated from the main shaft whereby a partial rotation and return is imparted to the purler-finger relative to the needles, and means, as described, whereby 30 at each end of the button-hole the path of vibration of the purler-finger is altered, whereby said finger operates ahead of the needles both at the forward and at the backward movement of the goods, substantially as set 35 forth.

2. In a button-hole sewing-machine, the combination, with the main shaft, the needle-bar and needles, the loop-taker, and the threaded purler-sleeve arranged around the 40 needle-bar and carrying the purler-finger, of the transverse shaft journaled in the head, the sleeve splined thereto and having thereon a spiral pinion, the cam-actuated rock-shaft and arm driven from the main shaft, whereby 45 longitudinal movement along its spline is imparted to the sleeve and pinion, and means, as described, whereby at predetermined times partial rotation may be imparted to the transverse shaft and the purler sleeve turned about 50 the needle-bar, substantially as specified.

3. In a button-hole sewing-machine, the combination, with the needle-bar, the needles, the loop-taker, and the vibratory purler-finger, of the ratchet-wheel having therein a cam- 55 groove, the lever operated by said cam, the slide-bar and cloth-plate arranged in the bed and operated forward and backward by the lever, and the presser-foot carried upon said slide-bar whereby the goods are clamped to 60 the cloth-plate, substantially as set forth.

4. In a button-hole sewing-machine, the combination, with the needles, purler, and loop-taker and means for operating them, of the ratchet-wheel within the arm and provided with the cam-groove, the cam on the 65 main shaft, the ratchet-operating pawl and the adjustable connection between said pawl

and the cam on the main shaft, the feed-lever actuated by the cam on the ratchet-wheel, and the slide-bar and cloth-plate operated 70 lengthwise of the bed by said lever, substantially as set forth.

5. In a button-hole sewing-machine, the combination, with the stitching mechanism, of the cloth-clamp and presser-foot, the slide-bar and the carriage in which it has its bearing, and the means for imparting to said slide-bar its longitudinal movement, the bell crank-lever connected to the carriage, the swinging block to which the said bell-crank 80 is also connected, and the cam-actuated lever whereby said block is turned and the traverse of the carriage accomplished, substantially as set forth.

6. In a button-hole sewing-machine, the 85 combination, with the reciprocating needle-bar, the needles, and the loop-taker, of the purler-sleeve arranged about the needle-bar and the purler-finger depending from said sleeve, the transverse shaft having splined 90 thereto a sleeve bearing a spiral pinion engaging the purler-sleeve and having at its end a spur-pinion, the rock-shaft and depending arm whereby a movement longitudinal of its spline is imparted to the sleeve, and 95 the rack bell-crank and cam-actuated lever whereby partial rotation is imparted to the transverse shaft for the shifting of the purler-finger, substantially as specified.

7. In a button-hole sewing-machine, the 100 combination, with the stitching devices and the purler and means for vibrating the same, and the longitudinally-movable slide bar and cloth-plate arranged in ways in a carriage in the bed, of the ratchet-wheel within the arm, 105 the cam in said wheel, and the lever 41, operated by said cam, the bell-crank and connections whereby the lower end of said lever operates to traverse the carriage, and the bell-crank, connecting-rod, and rack and pinion, 110 whereby the upper end of said lever operates to rotate the transverse shaft in the head of the machine and to change the path of vibration of the purler-finger, substantially as set forth.

8. The combination, with the stitching devices, the purler, and the feeding mechanism in a machine of the character described, of the cutter-bar arranged in the head of the machine and carrying the cutter, the cam-operated segment driven from the main shaft, means, as a lever and link interposed between the cutter-bar and segment, for connecting the cutter-bar and segment, and, further, means for automatically varying the engagement of 120 the link and segment, whereby when said link is engaged with said segment away from the pivotal point thereof a vertical reciprocation is imparted to the cutter-bar and when said link is over the pivotal point of said segment the cutter is idle and is withdrawn from operative position, substantially as set forth.

9. In a button-hole sewing-machine, the combination, with the main shaft, the stitch-

ing mechanism, and the vibratory purler-finger, of the vertically-sliding cutter-bar and cutter, the vibratory segment driven from the main shaft, the lever and link whereby 5 the cutter-bar is connected to said segment, the connection 72, and the cam-actuated lever whereby through said connection the cutter-bar is thrown into action or is withdrawn from operative position, substantially as 10 specified.

10. In a button-hole sewing-machine, the combination, with the stitching mechanism and the purler, the cloth-clamp and slide-bar, and the carriage in which they are mounted, 15 of the transverse shaft at the rear of the arm, the ratchet-wheel mounted at one end of said shaft and the disk at the other end, the cam-actuated bell-crank driven from the main

shaft and the ratchet-driving pawls operated from said bell-crank, the cam at one side of 20 the ratchet-wheel and the connections with said cam whereby the longitudinal feeding of the goods is accomplished, the cam at the other side of said wheel and the lever operated by said cam, whereby the traverse of the 25 carriage and the shift of the purler are accomplished, and the cam in the disk 70 and its connection with the cutter-bar, whereby the latter is caused to operate or is withdrawn from action, substantially as set forth. 30

In testimony whereof I affix my signature in presence of two witnesses.

FRANCIS T. LEILICH.
